UNITED STATES PATENT OFFICE.

JOHN ELKANAH WHITESIDE, OF ALEXANDER, LOUISIANA.

REINFORCED CEMENT ROOFING.

1,425,564.

Specification of Letters Patent. Patented Aug. 15, 1922.

Application filed January 26, 1921. Serial No. 440,000.

To all whom it may concern:

Be it known that I, JOHN E. WHITESIDE, a citizen of the United States, residing at Alexander, in the parish of Rapides and State of Louisiana, have invented certain new and useful Improvements in Reenforced Cement Roofing, of which the following is a specification.

This invention relates to new and useful improvements in reenforced cement roofing and has for its object to provide a reenforced shingle or roofing that will possess greater strength and durability than any product of this kind now on the market.

15 In the accompanying drawings, which are for illustrative purposes only and are therefore not drawn to scale:—

Fig. 1 is a perspective view, illustrating a shingle embodying my improvements.

20 Fig. 2 is a central longitudinal section, taken on line 2—2 of Fig. 1.

Fig. 3 is a vertical transverse section, taken on line 3—3 of Fig. 1.

25 Fig. 4 is a perspective view of the shingle prior to the application of the waterproof coating.

Fig. 5 is a horizontal section, taken on line 5—5 of Fig. 4, and Fig. 6 is a detail fragmentary sectional view, with the parts 30 represented on an enlarged scale.

Referring to the drawings for a more particular description of the invention and in which drawings like parts are designated by like characters throughout the several views, 35 the numeral 1 represents the base of the shingle or roofing which is formed of cement or other plastic material. In carry-

ing out my invention, the base 1 is reenforced by a strip 2 of wire gauze or other reticulated material, which is disposed between the 40 top and bottom faces of the shingle and extends the entire length and width of the base. The top and bottom faces 3 and 4 of the base 1 as well as the ends and side edges are treated or covered by a waterproof coat- 45 ing 7.

In practice, the side edges and ends 8 and 9, respectively, of the re-inforcing strip 2 may be slightly exposed, as shown more particularly in Figs. 4 to 6, inclusive, to provide 50 a more effectual binding between the base and waterproof coating at these points.

It will be understood that the shingle or roofing may be made of any desired dimensions.

55 From the foregoing description taken in connection with the drawings, it is thought that the construction, operation and advantages of this invention will be readily understood without requiring a more extended 60 explanation.

Having described my invention, what I claim as new and desire to secure by Letters Patent, is:—

A roofing material comprising a base of 65 plastic material reenforced by a strip of reticulated material disposed between the top and bottom faces of the base and extending the entire length and width thereof with its side and end edges exposed and a waterproof 70 coating enveloping the plastic base.

In testimony whereof I affix my signature.

JOHN ELKANAH WHITESIDE.
